(57) **CLAIM**

The ornamental design for a shelf for stereo, as shown and described.

DESCRIPTION

FIG. 1 is a perspective view of a shelf for stereo, showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is another perspective view thereof;

FIG. 9 is a first operational view showing a stereo system placed on the shelf; and,

FIG. 10 is a second operational view showing speakers placed on the shelf.

The broken lines illustrate portions of the shelf for stereo which form no part of the claimed design.
